LANTERN

Charles Irwin Rosen, Englewood, N.J., assignor to Emerson Electric Company, Artolier Division, St. Louis, Mo., a corporation of Missouri

Filed Mar. 7, 1966, Ser. No. 1,315

Term of patent 14 years

(Cl. D48—4)

FIG. 1 is a front view of a lantern embodying my new design.

FIG. 2 is a side view of the lantern; and

FIG. 3 is a top plan view of the lantern.

I claim:

The ornamental design for a lantern, as shown.
